UNITED STATES PATENT OFFICE.

FRANK A. BROWNE, OF BUFFALO, NEW YORK, ASSIGNOR TO THE BARBER ASPHALT
PAVING COMPANY, OF PHILADELPHIA, PENNSYLVANIA, A CORPORATION OF
WEST VIRGINIA.

TANDEM ROLLER.

1,322,092.

Specification of Letters Patent.

Patented Nov. 18, 1919.

Application filed February 12, 1917. Serial No. 148,173.

To all whom it may concern:

Be it known that I, FRANK A. BROWNE, of Buffalo, in the county of Erie and State of New York, have invented certain new and useful Improvements in Tandem Rollers, whereof the following is a specification, reference being had to the accompanying drawings.

My invention relates to the utilization of the roller or rollers of a tandem roller, as the receptacle for the water or liquid fuel which is used to drive the engine or motor. My device is equally applicable to a steam-driven roller, in which case water is thus stored, or to a vehicle driven by a motor using any form of liquid fuel which may be similarly stored. According to my invention the roller is provided with openings and pipe connections, whereby water or other liquid may be continuously fed into and as continuously withdrawn from the interior of the roller, notwithstanding the rotation of the same in the operation of the tandem roller.

To this end I provide a non-rotating axle about which the roller rotates, having inlet and outlet ducts, whereby the liquid fuel may be admitted to and withdrawn from the interior of the roller. I further provide a downwardly projecting extension in connection with the outlet duct, which can always reach the liquid in the lower portion of the roller, irrespective of its rotation.

In the accompanying drawings, Figure I, is a side elevation of the rear roller of a tandem roller, certain adjoining parts being also shown.

Fig. II, is a central vertical section along the line II, II, of Fig. I.

I have shown my invention as applied to the rear or driving roller of a tandem roller, but it is to be understood that it is not thus limited.

The invention comprises generally a low roller 1, rotatably mounted on the fixed axle or shaft 3, which, in turn, is provided with inlet and outlet ducts 12, and 11, respectively.

Roller 1, is provided on one side with a beveled gear 8, by which it may be driven through any appropriate mechanism. Bosses 2, are formed on the inside of roller 1, and projects inwardly at the axis thereof, forming journal boxes which rotate about axle 3.

Axle 3, is prevented from rotation by set screws 5, by means of which it is held in place and fixed in bracket blocks 6, which are in turn rigidly bolted to the side frame 7, of the roller. Roller 1, therefore, rotates about axle 3, and a sufficiently tight joint is provided by stuffing boxes 10, to effectually prevent the escape of any liquid contained within the roller.

In order to provide for the admission of the fluid into the interior of roller 1, I provide axle 3, with an axially located duct 12, extending from one end of the axle to a point well within the roller, where it connects with duct 17, which leads to the interior of roller 1. The outer end of duct 12, is connected with a pipe 15, which leads to a covered storage receptacle 16, which may be filled from a hose or bucket or other source of supply.

The fluid may be drawn from the roller by means of a similar duct 11, which is also formed axially of shaft 3, but extends to the opposite end from that of duct 12. At its exterior end it is connected with a pipe 13, which passes to a feed pump or injector, as the case may be, whereby the water, fuel, or other liquid in the interior of the roller may be continuously withdrawn from the roller during its rotation. The interior end of duct 11, which is well within the roller, beyond the limits of boss 2, is connected with pipe 18, which extends downwardly reaching almost to the bottom of the roller, so that liquid may always be withdrawn from the bottom of the roller, irrespective of its position. Pipe 18, may be conveniently provided at its lower end with a suitable strainer 19.

With this arrangement the roller may be maintained continuously filled with liquid from which at all times a supply may be drawn by the feed pump or injector, which withdrawal in itself effects a replacement of a similar amount within the roller, from the storage receptacle. For purposes of construction of asphalt roads, it is highly advantageous to have the compressing roller continuously filled with liquid for the purpose of absorbing the heat of the asphalt surface, upon which the roller runs. It is similarly advantageous to preheat the water or other liquid before feeding it to the boiler. It is likewise desirable that the roller be at

all times continuously filled with liquid in order that its center of gravity may be maintained constant.

The roller may be also provided with a manhole 22, and a gage 20, if desired. There may further be provided near the bottom of the roller a plugged opening 24, for filling from a pipe line or for draining the interior of the roller.

10 It is obvious that my invention is not limited to the precise form shown, but may be altered as to design of structure and detail, without departing from the spirit thereof.

15 Having thus described my invention, I claim:

In a self-propelled vehicle, the combination of a non-rotating axle; a closed hollow roller, capable of acting as a tank for liquid, 20 rotatably mounted thereon; said roller being

provided with packed journal boxes around said axle; said axle having inlet and outlet ducts formed therein, and extending from each end of said axle to points within the interior of the roller; a receptacle for liquid 25 with which the inlet duct is in communication; a motor connection with which the outlet duct is in communication; whereby liquid may be continuously drawn from the receptacle, through the hollow roller, and 30 fed to the motor, the interior of the roller being thus constantly wholly filled with said liquid.

In testimony whereof, I have hereunto signed my name, at Buffalo, New York, this 35 sixth day of February, 1917.

FRANK A. BROWNE.
